United States Patent

Des. 235,706
Patented July 8, 1975

235,706

MUSIC STAND

Neil Douglas Pennington, 622 Braeside Road,
Baltimore, Md. 21229

Filed Jan. 24, 1974, Ser. No. 436,172

Term of patent 3½ years

Int. Cl. D6—99

U.S. Cl. D6—18

FIG. 1 is a perspective view of a music stand showing my new design;

FIG. 2 is a perspective view of the rear thereof;

FIG. 3 is a left side elevational view;

FIG. 4 is a face view of the upper portion of a modified form of my new design, the undepicted portions being the same as those depicted in FIGS. 1, 2 and 3; and

FIG. 5 is a face view of the upper portion of another modified form of my new design, the undepicted portions being the same as those depicted in FIGS. 1, 2 and 3.

I claim:

The ornamental design for a music stand, substantially as shown and described.
